TOY

John J. Collins, San Francisco, Calif.

Application December 4, 1936, Serial No. 114,181

3 Claims. (Cl. 273—97)

My invention relates to improvements in toys, and it consists of the combinations, constructions and arrangements hereinafter described and claimed.

5 An object of my invention is to provide a toy which makes use of a bat and a rubber ball connected to the bat or paddle by means of a rubber string, and the principal novelty of the invention lies in the provision of an opening in the paddle 10 slightly less in diameter than the rubber ball, whereby the ball may be forced into the opening and be held in position when the device is not in use. Without such an opening it is difficult to connect the ball to the paddle so that the two can 15 act as a unit.

It is obvious that other means than the opening may be resorted to such as a spring clamp connected to the paddle and yieldably engaged with the ball. I have found, however, that an opening 20 in the paddle is the best means of support for the ball when not in use, and this opening would not interfere with the normal use of the device.

I provide novel reinforcing means for the paddle which enables the paddle to be formed from a 25 light inexpensive wood or from a composition material, such as fiberboard. I preferably dispose the opening between the batting area of the paddle and the handle. In this way the opening will not interfere with the striking surface of the 30 paddle, nor will it interfere with the hand grip portion of the handle. The opening preferably is reinforced by a rim of metal, and the sides of the paddle also are preferably reinforced at points 35 adjacent to the opening. In this way the paddle is strengthened sufficiently to offset any weakness inherent in placing the opening in the paddle.

The device is extremely simple in construction, and is durable and efficient for the purpose intended. If desired, staples may be placed on opposite sides of the opening, and between the opening and the reinforcing rim portions of the paddle. The staples will prevent cracking or breaking 40 of the material adjacent to the opening. All of the reinforcing members are preferably imbedded in the paddle so as to lie flush with the striking surface.

Other objects and advantages will appear in the following specification, and the novel features 50 of the device will be particularly pointed out in the appended claims.

My invention is illustrated in the accompanying drawing forming a part of this application, in which—

55 Figure 1 is a plan view of the device;

Figure 2 is a section along the line 2—2 of Fig-
1; and

Figure 3 is a section along the line 3—3 of Fig-
ure 1.

In carrying out my invention I provide a bat 5 or paddle indicated generally at 1. The paddle has a batting area indicated at 2, and a handle shown at 3. The bat may be made from any material desired, such as wood, laminated wood, composition material, such as fiberboard, etc. I 10 have found that if the bat is made approximately one-quarter of an inch thick, sufficient strength is afforded.

The batting area may be of any size desired, and I have found that a five and one-half inch 15 diameter provides an area of ample size. The length of the paddle including the handle is preferably eleven inches, and the shank 4 of the handle is about one and one-quarter inches across. The end of the handle is in the shape of a circle 20 with a diameter of about one and three-quarter inches. I do not wish to be confined to these measurements because they are merely set forth to give the desired proportions to the paddle.

The rubber ball indicated at 5 is connected to 25 the paddle by a rubber string 6 and a staple 7 or other suitable fastening means. The staple preferably is disposed near the center of the batting area 2. The rubber string may be of any length desired, and I have found that a string two and 30 one-half feet in length is sufficient. The string may be secured to the ball in any manner desired, and I have shown it extending diametrically through the center of the ball and a knot 8 is formed in the string to prevent the ball from 35 pulling loose. The ball has a diameter of one and three-eighths inches, although it is obvious that the size of the ball may be varied at will.

Any means desired may be used for attaching the ball to the bat when the device is not in use. 40 The simplest means is the provision of an opening indicated generally at 9, the diameter of this opening being slightly less than the diameter of the ball, so that the ball will frictionally engage with the wall of the opening when the ball is placed in 45 the opening, and in this way the ball will remain attached to the bat until the device is used again. If desired, the opening may be reinforced by an eyelet 10 of metal, or other suitable material. The eyelet has flanges 11 and 12 that lie 50 flush with the outer surfaces 13 and 14 of the paddle, see Figure 3. Figure 2 shows the ball 5 disposed in the eyelet and frictionally held in position.

The opening 9 may be placed in any desired 55

position on the paddle. The best location seems to be on a curved line *a* that is a continuation of the batting area periphery. The center of the circle lies on the curved line, and is disposed mid-way between the sides 15 and 16 of the shank or neck portion 4.

It is obvious that the placing of an opening 9 at the narrow portion of the paddle will weaken this portion. The flanges 11 and 12 of the eyelet 10 will tend to overcome this weakness because the eyelet flanges and the eyelet itself acts as a reinforcing member not only to the opening 9, but also to the area adjacent to the opening. In addition I provide staples 17 and dispose these on opposite sides of the opening. Figure 3 shows the staples as extending substantially throughout the thickness of the paddle. The U portions of the staples are imbedded in the surface 13 so as not to interfere with the striking area. The staples may be of any desired length, and are preferably equal to the diameter of the opening.

The edges of the shank 4 may also be reinforced adjacent to the opening 9. In Figures 1 and 3 I show reinforcing channels 18 crimped into the paddle so that the flanges 19 of the channels will lie flush with the surfaces 13 and 14. Although the drawing shows the channels extending a short distance along the shank 4 and paddle portion 2, it is obvious that a single channel may be used 30 and extend around the entire edge of the paddle and handle.

From the foregoing description of the various parts of the device, the operation thereof may be readily understood.

35 In playing with the toy the ball 5 is removed from the eyelet 10, and then the handle 3 is grasped in the hand. The paddle may be used

for merely striking the ball and the rubber string 6 will return the ball, the object of the toy being for the player to again strike the ball. Many tricks can be accomplished with the toy. The opening 9 does not interfere with the striking area, and provides a simple means for attaching the ball to the paddle when the device is not used. This manner of attachment is the principal object of the invention.

While I have shown only the preferred form of my invention, it should be understood that various changes or modifications may be made within the scope of the appended claims without departing from the spirit of the invention.

I claim:

1. In combination, a paddle with a striking area and a handle, said paddle being provided with a ball-receiving opening at the place where the handle merges into the ball striking area, the wall of the opening being reinforced and having a diameter slightly less than the ball for frictionally engaging with the ball, and auxiliary paddle reinforcing means disposed adjacent to the opening.
2. In combination, a paddle having a handle and a ball receiving opening, reinforcing staples disposed adjacent to the opening, and reinforcing channels engaging with the edges of the paddle disposed adjacent to the opening.
3. In a device of the type described, a paddle having a handle, said paddle being provided with an opening between a ball striking area and the handle, and a reinforcing eyelet for the opening having flanges abutting opposite surfaces of the paddle said eyelet being large enough to snugly receive a ball.

JOHN J. COLLINS.
